US0D1106983S

(12) **United States Design Patent** (10) Patent No.: **US D1,106,983 S**
(45) Date of Patent: ** Dec. 23, 2025

(54) **CONTROL DEVICE**

(71) Applicant: **Lutron Technology Company LLC**,
Coopersburg, PA (US)

(72) Inventors: **Gregory Altonen**, Easton, PA (US);
Chris Dimberg, Easton, PA (US);
Jason C. Killo, Emmaus, PA (US)

(73) Assignee: **Lutron Technology Company LLC**,
Coopersburg, PA (US)

(**) Term: **15 Years**

(21) Appl. No.: **29/985,341**

(22) Filed: **Jan. 16, 2025**

Related U.S. Application Data

(63) Continuation of application No. 29/916,809, filed on Nov. 15, 2023, now Pat. No. Des. 1,061,458, which is a continuation of application No. 29/883,400, filed on Jan. 27, 2023, now Pat. No. Des. 1,009,812, which is a continuation of application No. 29/809,651, filed on Sep. 29, 2021, now Pat. No. Des. 978,092, which is a continuation of application No. 29/709,557, filed on Oct. 15, 2019, now Pat. No. Des. 933,615.

(57) **CLAIM**

The ornamental design for a control device as shown and described.

DESCRIPTION

FIG. 1 is a front perspective view of a control device showing our new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The broken lines depict portions of the control device which form no part of the claimed design.

1 Claim, 5 Drawing Sheets
